Attorney

UNITED STATES PATENT OFFICE.

RAY H. TRASK, OF BOISE, IDAHO.

STORAGE BUILDING FOR MOTOR VEHICLES.

Application filed September 3, 1925. Serial No. 54,218.

To all whom it may concern:

Be it known that RAY H. TRASK, a citizen of the United States, residing at Boise, in the county of Ada and State of Idaho, has invented certain new and useful Improvements in Storage Buildings for Motor Vehicles, of which the following is a specification.

This invention relates to the construction of a storage building particularly designed for the accommodation of motor vehicles.

The main object of the present construction resides in the provision of an arrangement which is of such a character as to permit the storage of motor vehicles in a safe and convenient manner and at the same time permit the movement of any such vehicles in storage with the greatest efficiency by permitting immediate access to each one independently of the adjacent vehicles.

Another object contemplates the utilization of a plurality of decks, each of substantially identical design, and the provision of an elevator to permit the loading and unloading of the decks above or below the street level.

More specifically, the present invention includes a building having one or more floors, each arranged in groups of parallel sets of motor vehicle spaces, and in the provision of means for rotating each floor to bring each independent motor vehicle space of each group into alignment with the loading or unloading means.

Other features reside in the novel details of construction embodied in the main building and in the supporting and driving means for the various floors, which features are designed to increase to the maximum the strength and durability of the moving parts involved in the assembly.

Other objects and results will more clearly hereinafter appear by reference to the accompanying drawings, forming a part of this specification, and wherein like numerals are of reference designate corresponding parts throughout the several views, in which:

Figure 1 is a vertical section through one form of my invention;

Figure 2 is an enlarged elevation showing the arrangement of supporting rollers and track;

Figure 3 is a similar view showing the driving means for the upper floor;

Figure 4 is a transverse section showing the plan of the floor; and

Figure 5 is a similar section showing the foundation and supporting roller.

The main building obviously may be constructed of any suitable material, although in the present instance the construction is illustrated as being formed of concrete, and comprises cylindrical wall A reinforced at spaced points by vertical I-beams B. The inner surface *a* of the wall is of circular contour and the outer surface *b* is shown as being octagonal in form, the web of the reinforcing elements being arranged to extend radially and to be located at the points of greatest thickness caused by the particular contour of the inner and outer surfaces.

The main floor C is supported by the outer foundation *c* and the central foundation *c'*, the latter supporting the central shaft or column hereinafter mentioned. A circular track D illustrated more clearly in Figure 5, is fixed to the floor C and upon this track the circular rotary first floor platform E is supported and travels. The platform E is braced by means of a plurality of I-beams F which radiate from the central hub G and terminate in engagement with the annular channel-beam H arranged flush with the outer periphery of the floor E. The inner extremities of the beams F engage the reduced portion *g* of the hub G and rest upon the upper face of the enlarged portion *g'*. A plurality of grooved rollers J are supported by the hangers *j* at suitably spaced points to the beams F and travel on the track D. The hub G rests upon roller bearings K carried by bearing support *k*. From the foregoing the strength and equal balance of the floor E will be apparent and such strength and rigidity has been found essential due to the movement of the platform both in fully loaded and partially loaded condition.

A central vertical shaft on column M extends axially through the hub G and to the top of the building. In the event that the building is of considerable height, this shaft M may be made in sections, each section extending through one or more floors as may be determined by varying conditions and circumstances.

In the present instance, a ceiling N is shown as spacing the upper and lower

5 floors and the track for the upper floor indicated by reference character P is supported by a series of spaced brackets Q as illustrated more clearly in Figure 3. This bracket is shown as including a central downwardly extending web portion q for the purpose of increasing the strength of these elements.

10 For rotating the various platforms, annular racks R are provided, the racks being fixed to the radiating reinforcing I-beams between the rollers J and the I-beam extremities. In Figure 4 the motor S is shown as having the drive pinion r in mesh with the rack R. The arrangement and control of the drive means for the various platforms may be varied in accordance with the necessities of each case, the present illustration being more for the purpose of disclosing an 15 operative arrangement.

20 On a level with each storage platform, a door is provided to permit the passage of the loading or unloading vehicle and an elevation T of suitable design may be utilized to 25 elevate or lower the vehicles to the desired floor.

25 The design of the loading platform is of considerable importance and is such as to permit the complete enclosure of all vehicles except the one entering or leaving. In other words, only one vehicle is in a position to be moved, even on the ground floor, although by a single operation the particular vehicle to be placed in this position may be selected indiscriminately. The foregoing is accomplished by the arrangement clearly illustrated in Figure 4. In this figure it will be noted that the circular rotating receiving platform is divided equally from its axis as determined by the shaft M, into four sectors or quarters by the partitions V and each section as thus divided is spaced into four additional equal sections by the partitions W. The partitions W extend from the partitions V in groups, each group being at right angles to each adjacent group, thereby forming stalls in groups of three. By this arrangement the individual stalls of each group may be brought into convenient position for loading or unloading from the elevator T and when in this position all other vehicles, such as may be in storage, are safe from tampering or unloading.

55 The present illustration has been directed more particularly to a building provided with circular platforms. Obviously, however, both the building and the platforms may be of any desired design. This latter is especially true where the present invention is to be embodied as an element of an office building, apartment, hotel, or the like, in which event the particular shape of the garage and the storage platform will be controlled primarily by the structure of the

65 building of which it forms a part. In some instances a series of these garages may be included in a single unit or they may be arranged at different points in the structure of the main building.

70 I claim:

1. A storage floor for motor vehicles comprising a series of groups of parallel parking sections, each of said groups being arranged at right angles to the adjacent group, and means for moving said storage 75 floor to permit the movement of said vehicles.

2. In a storage building including a cylindrical outer wall having a door, a central vertical shaft within said building, a platform, said shaft extending through the center of said platform and forming an axis therefor, supporting means for said floor, including a bearing on the said shaft, a plurality of groups of parking spaces, and means for 80 moving said platform to bring the individual parking sections adjacent said door.

3. In a storage building including an outer wall having a plurality of vertically aligned doors, a central shaft extending upwardly within the building, a plurality of storage floors arranged on said shaft, a circular track beneath each storage floor, rollers carried by said storage floor and adapted to travel on said track, groups of 85 parking spaces outlined on said storage floors, and means for moving said floors to bring each parking space of each floor adjacent to the proper door.

4. In a storage building for motor vehicles including an outer wall having a discharge passage, a rotary storage floor within said building, and parking spaces outlined on said floor comprising groups of three parking spaces, each group being arranged at right angles to each adjacent group on the four-quarter sections of the circular floor surface, the groups being outlined by radiating marks extending at each 90° from the central axis.

5. In a storage building including a wall, a plurality of supporting members extending inwardly from the wall, an annular track carried by said supporting members, a platform, supporting rollers for said platform adapted to travel on said track, and driving means for said platform positioned without the building including a rack, a motor having a drive shaft extending through the wall and a pinion on the extremity of said shaft engaging said rack.

6. In a storage building including a wall having a doorway and a fixed floor, a central support for said floor, a bearing carried by said central support, a standard, a collar on said standard adapted to seat on said bearing, a trackway, a platform having rollers adapted to travel on said trackway

and being supported adjacent its center by said collar, and means for driving said platform.

7. In a storage building including a wall 5 having a doorway and a fixed floor, a central support for said floor, a bearing carried by said central support, a standard, a collar on said standard adapted to seat on said bearing, a trackway, a platform having 10 rollers adapted to travel on said trackway and being supported adjacent its center by said collar, and means for driving said platform, positioned without the building including a rack, a motor having a drive 15 shaft extending through the wall and a pinion on the extremity of said shaft engaging said rack.

8. A rotary storage platform for motor vehicles having groups of spaces defined for 20 motor vehicles by means of a plurality of

markers radiating from the axis at right angles to each other and other lines defining individual spaces extending at right angles to the group markers.

9. A rotary storage platform for vehicles 25 having groups of spaces defined for motor vehicles by means of a plurality of markers radiating from the axis at right angles to each other, other lines defining individual spaces arranged parallel to each other and at 30 an angle to the group markers.

10. A storage floor for motor vehicles comprising a series of groups of parallel parking sections, each of said sections being arranged at an angle to the adjacent group, 35 and means for moving said storage floor to permit the movement of said vehicles.

In testimony whereof I affix my signature.

RAY H. TRASK.
